D. MCKAY

TONSIL HEMOSTAT

Filed Oct. 20, 1923

FIG. 6.

25 INVENTOR
D. MCKAY.,
BY *Illustrating Socy*

Patented Dec. 15, 1925.

1,565,481

UNITED STATES PATENT OFFICE.

DONALD MCKAY, OF COLLINGWOOD, ONTARIO, CANADA.

TONSIL HEMOSTAT.

Application filed October 20, 1923. Serial No. 669,756.

To all whom it may concern:

Be it known that I, DONALD MCKAY, a subject of the King of Great Britain, and a resident of the town of Collingwood, in the 5 county of Simcoe, in the Province of Ontario, Canada, have invented certain new and useful Improvements in Tonsil Hemostats, of which the following is the specification.

My invention relates to improvements in 10 tonsil hemostat and the object of the invention is to devise a hemostat which may be readily inserted and adjusted in the proper position within the throat of the patient so as to produce a direct pressure against the 15 tonsil beds and which will therefore be efficient to a maximum extent and at the same time provide a device which may be used without discomfort to the patient, and it consists essentially of a pair of pressure 20 plates adapted to fit the cavities or beds formed by the removal of the tonsils, means for detachably securing a covering pad to the plates, stems extending inward from the plates and telescopically engaging one with 25 the other, detachable means for locking the stems in any position to which they may be adjusted longitudinally and means for simultaneously releasing such locking means and drawing the plates inward free of the 30 tonsil beds, as hereinafter more particularly explained by the following specification.

Fig. 1 is a perspective view of my hemostat, the pressure springs being removed.

Fig. 2 is an enlarged longitudinal section view through the hemostat.

Fig. 3 is a plan view of my hemostat.

Fig. 4 is a cross sectional view on the line 4—4 Figure 3.

Fig. 5 is a cross sectional view on the line 40 5—5 Figure 3.

Fig. 6 is an alternative form of pressure member.

Fig. 7 is a fragmentary detail of the stem 3.

45 In the drawings like characters of reference indicate corresponding parts in each figure.

1 and 2 indicate plates, the outer surfaces of which are convex. The plates are of such 50 a form as to fit the cavities or beds formed by the removal of the tonsils. 3 and 4 are stems extending inwardly respectively from each plate 1 and 2. The stem 4 is provided with a tubular inner portion as indicated at 55 5 into which the smaller stem 3 slidably fits so as to form a telescopic connection. 6 is a

longitudinal slot formed in the stem 3 and 7 is a longitudinal slot formed in the stem 4. 8 is a sleeve provided at one end with a reduced internal diameter forming an orifice 9 60 through which the stem 3 passes. The stem 4 extends into the opposite end of the sleeve so as to engage with the stem 3 in an overlapping position, as clearly indicated in Figure 2. The stem 3 is provided with a series 65 of ratchet teeth 10, the vertical face of each tooth facing inward.

11 are teeth which are formed in the stem 4 and correspond in form to the teeth 10. 12 is a spring locking member comprising a strip of metal secured by a cross rivet 13, extending centrally through the sleeve 8 and through the overlapping portions of the slots 6 and 7. By means of the rivet 13 it will be seen that the outward movement of the stems is limited by the end of each slot engaging with a rivet at the end of the longitudinal movement of each stem. The spring locking member 12 is provided with down turned 70 ends 14 and 15 respectively engaging the teeth 10 and 11. 16 and 17 are eyes extending from the plates 1 and 2. 18 and 19 are levers extending around the sleeve 8 in proximity to each end thereof and provided with a cross bar portion 20 extending cross-wise 75 of the sleeve 8 through a recess 8^x formed therein, thereby extending directly beneath the free end of the spring locking member 12. 80

The levers 18 and 19 incline inward and have attached to their inner ends operating cords 21 and 22 which extend from the operating ends of the levers 18 and 19 through the eyes 16 and 17, and when the device is in position in the throat extend out through the 90 mouth of the patient. 23 are gauze pads which are folded around the plates 1 and 2 and are secured in position by the following 95 device:

24 are plates which are preferably formed 100 of thin spring metal and divided into two members 24^x and 24° pivotally connected together by a pivot pin 25. 26 is a spring which is wrapped around the pin 25 and engages at its free end pins 27 and 28 so as to 105 normally exert inward pressure upon such pins and carry the edges of the plate members 24^x and 24° into contact, each plate member 24^x and 24° being provided with a semicircular recess 28^x forming an orifice 110 through which the stem 3 or 4 extends. 29 are a series of ratchet teeth formed on the

side face of each stem 3 and 4 or in a position at right angles to the teeth 10 and 11.

The teeth 29 are set in an opposite direction to the teeth 3 and 4, that is to say with a vertical face of the tooth facing outward. When the gauze pad is wrapped around the edge of the plate 1 or 2 the free ends of the gauze are folded inward and the plate 24 forced against the edges of the gauze so as to clamp them between the plate 24 and the plate 1 or 2. The plate 24 is also provided with inturned projections 30 which engage the gauze and serve to provide a clamping hold thereon.

15 When removing the pad all that is necessary to do is to spread the free ends of the divided portions 24^x and 24^y of the plates 24 apart so as to free them from the ratchet teeth 29 and permit the plates being slid 20 longitudinally of the stem 3 or 4 so as to disengage the pad.

25 31 are pressure springs extending between the ends of the sleeve 8 and the plates 24 exerting an outward pressure against such plates so as to resiliently hold a pad in contact with the tonsil beds. The ends of the sleeve 8 are preferably notched as indicated at 8° so as to relieve the inturned ends 14 and 15 of the spring locking member 12 from contact with the springs 31.

Having described the principal parts involved in my invention I will briefly describe the operation of the same.

36 After the pads have been placed upon the plates 1 and 2 as above described, the cords 21 and 22 are drawn upon so as to carry the inturned ends 14 and 15 out of contact with the teeth 10 and 11 of the stems 3 and 4, permitting the stems to be slid longitudinally inward of the sleeve 8. The sleeve 8 is then gripped by a pair of forceps and the hemostat inserted in the throat of the patient. Each stem is then drawn outward by another pair of forceps so as to successively force the plates 1 and 2 and the pads carried thereby into contact with the tonsil beds, the inturned ends 14 and 15 slipping over the ratchet teeth 10 and 11 during this operation. When the plates 1 and 2 and the pads are in position the inturned ends 14 and 15 engage the shoulders formed by the vertical faces of the teeth 10 and 11, thereby holding the pads securely in position in the tonsil beds to prevent further bleeding.

55 The springs 31 serve to exert a resilient pressure so that the pads accurately accommodate themselves to the depth of the bed. When it is desired to remove the hemostat all that is necessary to do is to pull upon the cords 21 and 22, thereby swinging the levers 18 and 19 towards a position at right angles to the longitudinal centre of the sleeve 8, thereby lifting the free ends of the spring locking member 12 out of engagement with the teeth 10 and 11 of the stems 3 and 4.

The pull upon the cords 21 and 22 also exerts an inward draw upon the plates 1 and 2 so that immediately the stems 3 and 4 are released, such plates are drawn inward and out of the tonsil beds, permitting the instrument to be drawn out of position through the mouth of the patient

70 In Figure 6 I have shown a modified form of pressure plate. In this form the plate or member is formed by a strip of flat spring 75 wire wound into a helical coil, the inner end of the wire being connected to a central stem and the end of the outer turn to the next adjacent turn. By this means a pressure member is formed which will accommodate itself 80 exactly to the formation of the tonsil bed. It will of course be understood that a pad such as previously described in connection with the foregoing construction is also applied to the construction shown in Figure 6. 85

90 From this description it will be seen that I have devised a very simple device which is very efficient for the stopping of hemorrhages occurring after the removal of tonsils, by producing a direct and even pressure into the tonsil bed, and which may be readily adjusted into position and which obviates the use of any device not forming part of the hemostat which is held in the mouth of the patient during the time that the hemostat is in position within the throat, and therefore preventing the gagging effect and the consequent discomfort to the patient during the time that the hemostat is within the throat. 95

100 What I claim as my invention is:

1. In a tonsil hemostat, a pressure plate adapted to support a pad and to fit a tonsil bed, means engaging the opposite side of the throat, means located between such engaging means and the pressure for forcing the pressure into the tonsil bed, and a pull cord operable from the exterior of the patient's mouth for withdrawing the pressure plate out of engagement with the bed. 105

2. In a tonsil hemostat, a pair of oppositely directed plates adapted to carry pads fitting the tonsil beds at each side of the throat, resilient means for forcing the plates apart, releasable locking means for holding the plates in the spread apart position, and flexible means operable from the exterior of the patient's throat for simultaneously releasing the locking means and withdrawing the plates out of engagement with the tonsil beds. 115

3. In a tonsil hemostat, a pair of plates adapted to carry pads engaging the tonsil beds, stems extending inward from the plates telescopically engaging one with the other, a covering sleeve extending around the engaging portions of the stems, means carried by the sleeve for locking the stems in the adjusted position, means for limiting the outward movement of the stems, and means 125 130

operable from the exterior of the patient's throat for simultaneously releasing such locking means and withdrawing the plates from the tonsil beds.

5. 4. In a tonsil hemostat, a central sleeve, a pair of stems slideable within the sleeves, means for detachably locking the stems in any position to which they may be adjusted and pad bearing means carried at the ends 10 of the stems for engagement with the tonsil beds.

5. 5. In a tonsil hemostat, a central sleeve, stems slideable within the sleeve and extending outward from each end thereof, a ratchet 15 rack formed on each stem, a spring locking member carried by the sleeve in engagement with each ratchet rack, means operable from the exterior of the mouth of the patient for withdrawing the inner portion of the locking 20 members simultaneously out of engagement with the racks and pad bearing means carried at the outer ends of each stem.

6. 6. In a tonsil hemostat, a pressure plate adapted to fit a tonsil bed and over the exterior face of which a pad is adapted to be 25

held so as to be folded around the edges of the plate against the inner face thereof, a stem extending outward from the pressure plate and a gripping plate divided into two portions and extending around the stem, 30 means for engaging the gripping plate with the stem in any position to which the gripping plate is adjusted, and resilient means for holding the members of the gripping plate together. 35

7. In a tonsil hemostat, a pressure plate over the exterior face of which a pad is adapted to be held so as to fold around the edges of the plate against the interior face of the plate, a stem extending from the pressure plate, a ratchet rack formed on the stem, a gripping plate divided into two portions pivotally connected together so as to fit around the stem and against the inner face of the pressure plate to engage the edges of the pad, projections extending inward from the gripping plate to engage the pad and resilient means for holding the free ends of the gripping plate members together. 40 45

DONALD McKAY.
